PLATE

Alfred Wright, Stoke-on-Trent, England, assignor
to Barker Brothers Limited, Stoke-on-Trent,
England

Application April 12, 1951, Serial No. 14,799

Term of patent 7 years

(Cl. D44—15)

To all whom it may concern:

Be it known that I, Alfred Wright, a citizen of Great Britain, residing at Meir Heath, Stoke-on-Trent, England, have invented a new, original, and ornamental Design for a Plate, of which the following is a specification, reference being had to the accompanying drawing, forming a part thereof.

Figure 1 is a top plan view of a plate showing my new design; and

Figure 2 is a cross-sectional view of the same. The dominant feature of the present design resides in the annular rim provided with a series of spaced apart flowers extending around the rim, the leaves projecting from each flower in opposite directions lengthwise of the rim, the flowers and leaves occupying substantially the entire width of the rim as shown.

I claim:

The ornamental design for a plate, as shown and described.

ALFRED WRIGHT.
